UNITED STATES PATENT OFFICE

172,394

REAR LIGHT FOR AUTOMOTIVE VEHICLES

Jack E. Kenitz, Detroit, Mich., assignor to Packard Motor Car Company, Detroit, Mich., a corporation of Michigan

Application August 10, 1953, Serial No. 26,388

Term of patent 14 years

(Cl. D48—32)

To all whom it may concern:

Be it known that I, Jack E. Kenitz, have invented a new, original, and ornamental Design for Rear Light for Automotive Vehicles, of which the following is a specification, reference being had to the accompanying drawing, forming a part hereof.

Figure 1 is a rear perspective of the rear light for automotive vehicles showing my new design.

Figure 2 is a side view of the design shown in Figure 1.

Figure 3 is a rear view of the design shown in Figure 1.

The adjacent vehicle fender portions shown by means of dotted lines are disclosed only for purposes of illustration.

I claim:

The ornamental design for a rear light for automotive vehicles, as shown and described.
